Design for Stores.*

Patented May 28, 1850.

Ms. 186

J. C. Bailey & R. Wheeler of Utica N.Y.
Letters Patent No. 286. Dated May 28. 1850.

The Schedule referred to in these Letters Patent and making part of the same.

To all to whom it may concern:

Be it known that we Joel C. Bailey & Rufel Wheeler of the City of Utica, in the County of Oneida, and State of New York all being citizens of the United States of America have by our own efforts and expense produced a new and original design for the plates of a Cooking Stove not known or used by others before our production thereof & we hereby declare that the following is a full and exact description.

The design consists in the manner of ornamenting the plates of a Cooking Stove and is shown in the annexed drawing to which reference is hereby made. The principal plates are ornamented with a row of raised bead work a short distance from the margin; within and parallel to it are ornaments formed by a vine. The plates forming the doors have a raised center raised by a cornice and the panel formed thereby is ornamented with vine work tracery, the whole of which distinctly appears upon the drawing.

What we claim as our invention and desire to secure by Letters Patent is the design of the form of the plates consisting of the peculiar manner the same are ornamented & constructed: We lay no claim to the general form of the Stove.

Witnesses.
